UNITED STATES PATENT OFFICE.

NICHOLAS S. VEDDER, OF TROY, AND TOBIAS S. HEISTER, OF LANSINGBURG,
ASSIGNORS TO NICHOLAS S. VEDDER, OF TROY, NEW YORK.

DESIGN FOR A COOKING-STOVE.

Specification forming part of Design No. 6,308, dated December 17, 1872.

To all whom it may concern:

Be it known that we, NICHOLAS S. VEDDER, of the city of Troy, in the county of Rensselaer and State of New York, and TOBIAS S. HEISTER, of Lansingburg, in said county and State, have jointly invented and produced a new and original Design for Cook-Stoves, of which the following is a specification, reference being had to the accompanying wood cut or engraving of a stove which embodies our said design.

One part of our invention consists of the compound ornament D, shaped and arranged on a door or panel of a stove, substantially as represented in the accompanying engraving. Another part consists of the ornament or ornaments E, shaped and arranged on a door or doors, or panel or panels, or leg or legs, of a stove, as represented in the aforesaid wood-cut. Another part consists of the combination of the border-molding F, panel G, and ornament D or E, as represented in the wood-cut, with or without the bead ornamentation H. Another part consists of the design for

the compound edge-moldings I of the top-plate J, hearth-plate K, and bottom plate L, as distinguished by the lower convex molding m, upper concave molding n, and intervening straight or flat sloping molding o, all shaped and arranged together in the particular form and manner represented in the aforesaid wood- engraving.

What we claim as our invention is—

1. The ornament D, shaped and arranged as herein described.
2. The ornament or ornaments E, shaped and arranged as herein set forth.
3. The combination of the border-molding F, panel G, and ornament D or E, as described.
4. The design for the compound edge-moldings I on the top, bottom, and hearth plates, as herein shown and described.

NICHOLAS S. VEDDER.
TOBIAS S. HEISTER.
